UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

FASTENER REMOVER.

Application filed May 22, 1922. Serial No. 562,915.

This invention relates to the removal of temporary fasteners such as are used to clamp heels to shoes and lasts, and is illustrated as embodied in a power-driven screw removing machine.

According to an improved method of attaching heels disclosed and claimed in co-pending application, Serial No. 367,173, filed March 19, 1920, in the name of M. V. Bresnahan, each heel is clamped temporarily against the heel seat of a shoe on a perforated last by means of a screw fastener passing through the perforation in the last and through the heel seat of the shoe into the heel. This fastener holds the last and shoe and heel tightly clamped together during the drying of the adhesive between the heel and shoe, while at the same time permitting the shoe to be finished during the drying of the adhesive, since the exterior of the shoe is entirely unobstructed.

An object of the present invention is to provide an improved screw removing machine for removing such temporary fasteners after they have served their purpose.

To this end, and as illustratively shown in the drawings, a novel form of power-driven continuously rotating screw-engaging tool is mounted in position to permit an operator freely to present the work thereto, and the tool itself is so constructed as to facilitate the establishment of turning engagement with the work without requiring the exercise of any particular amount of care on the part of the operator in the presentation of the work to the machine. Thus the operator may take shoes successively from a rack, present each shoe to the screw removing device and then return the shoe to the rack without losing time or finding it necessary to shift his hold upon the shoe. As the above-described screw fasteners are formed with heads in the form of circular eyes, the novel screw-engaging tool is formed with a substantially semi-spherical recess to receive such an eye, and a groove intersects the recess and is formed with parallel sides for embracing the eye of the fastener so as to enable the tool to turn the fastener. In order, however, to enable driving connections between the tool head and the fastener to be established without undue abruptness the eye-engaging groove is so designed that it terminates short of the bottom of the tool head so as not to interrupt

the continuity of the wall or surface at the mouth of the recess.

Other features of my invention, including specific constructions and combinations of parts will be apparent from the following description of the embodiment thereof illustrated in the accompanying drawings, wherein:

Fig. 1 is a side elevation of a screw removing machine partly broken away to show the operating mechanism;

Figs. 2 and 3 are elevations, partly broken away, at right angles to one another, showing the construction of the screw-engaging tool head;

Fig. 4 is a diagrammatic view showing the use of the machine; and

Fig. 5 is a plan view of the tool head shown in Figs. 2 and 3.

As shown in Fig. 1 the machine is driven from an electric motor 10 mounted on a suitable base 12 which may be formed to enclose a switch, or a switch and rheostat. A vertical shaft or spindle 14 carries a screw engaging tool or head 16 at one end and a bevel gear 18 at the opposite end which is arranged to be driven by a bevel gear 20 carried by the armature shaft 22 of motor 10. If desired, gears 18 and 20 may be arranged in a suitable casing to run in oil, as illustrated.

As best shown in Figs. 2 and 3, the improved screw removing tool or head 16 is formed with a semi-spherical recess or socket 24 of such a curvature as to fit over the eye or head of a temporary fastener such as shown at F in Fig. 4. An aperture 26 extends through the tool head 16 at right angles to the axis of the spindle 14, said aperture intersecting the axial center line of the tool head and opening into the base of the semi-spherical recess 24 to provide a groove or slot 28 adapted to receive the eye or head of the fastener, the groove having parallel sides to embrace the fastener for the purpose of turning the latter in a direction to unscrew it from the last. The groove 28 is so formed that it intersects the base of the recess 24 but terminates short of the widest portion of the fastener-receiving recess in the tool so that the groove does not interrupt the continuity of the wall or surface at the mouth of the recess. This construction permits the eye or head of the fas-

tener advantageously to be thrust against the smooth rim of the socket and introduced a substantial distance into the socket before turning engagement is established with the fastener. Thus the operator may present the work to the machine without exercising any particular care accurately to locate the fastener with respect to the driving slot in the tool. Thereafter positive driving engagement with the fastener may be effected merely by pressing the work toward the tool to seat the fastener head in the slot 28. The engagement of the tool with the fastener will thus be caused to take place smoothly and in such a manner as to avoid danger of breakage of the fastener irrespective of the speed at which the tool is revolving when the fastener is presented thereto. With this construction no time is lost in positioning the articles upon presentation to the machine, and thus the articles may be operated upon in rapid succession as is highly desirable.

Further to facilitate the entrance of the head of the fastener into the recess 24, the curvature of the portion of the tool which defines said recess is reversed at the mouth of the recess, as indicated in Figs. 2 and 3, so that the sides of the recess merge gradually with the lower face of the tool 16. This construction provides a flaring mouth which will tend to guide the head of the fastener into said recess, thus making it easier operatively to engage the tool with the fastener when the tool is rotating.

In operation, a rack containing a number

of lasts, shoes and heels clamped together by fasteners F, is placed near the improved machine and an operator takes them successively from the rack, presents them, rapidly and without the exercise of any great amount of care, to the machine for the removal of the fasteners, and then returns them to the rack.

While one embodiment of my invention has been illustrated and described, it is not my intention to limit its scope thereby or otherwise than by the terms of the appended claim.

Having described my invention, what I claim as new and desire to secure by Letters Patent of the United States is:

A device for removing screw fasteners of the type provided with a head in the form of a circular eye comprising a power-driven continuously rotating spindle and a tool head formed at one end of the spindle and having a substantially semi-spherical recess formed therein to receive the upper half of the head of a fastener, the tool head having also a groove opening into the bottom of the recess so as to receive the head of the fastener to turn the fastener, the groove terminating short of the widest part of the spherical part of the recess and the curvature of the surface defining the recess being reversed at the mouth of the recess to facilitate the entrance of the head of the fastener into the recess while the spindle is rotating.

In testimony whereof I have signed my name to this specification.

FREDERIC E. BERTRAND.
